CLAIM

The ornamental design for a karate staff, as shown and described.

DESCRIPTION

FIG. 1 is a side elevation view of one embodiment of the karate staff of this invention with the other three side elevational views each being the same view.

FIG. 2 is a view similar to FIG. 1 showing another embodiment of my karate staff with the other three side elevational views each being the same view.

FIG. 3 is a side elevation view similar to FIGS. 1 and 2, but showing another embodiment of my karate staff with the other three side elevational views each being the same view; and,

FIG. 4 is an end view of my karate staff for either FIGS. 1, 2, or 3 with the other end view being the same.
